(57) CLAIM

The ornamental design for a mug with a golf green and tee box, as shown and described.

DESCRIPTION

FIG. 1 is a perspective view of the mug with a golf green and tee box;

FIG. 2 is a front view thereof;

FIG. 3 is a back view thereof;

FIG. 4 is a right side view thereof;

FIG. 5 is the left side view thereof;

FIG. 6 is a top view thereof; and,

FIG. 7 is a bottom view thereof.

The ornamental design, which is claimed, is shown in solid lines in the drawings. Any broken lines in the drawings depict unclaimed portions of the mug with a golf green and tee box, and form no part of the claimed design.

1 Claim, 5 Drawing Sheets
